UNITED STATES PATENT OFFICE.

HERBERT PERCY SAUNDERSON, OF BEDFORD, ENGLAND.

PUMP.

SPECIFICATION forming part of Letters Patent No. 724,048, dated March 31, 1903.

Application filed May 2, 1902. Serial No. 105,596. (No model.)

To all whom it may concern:

Be it known that I, HERBERT PERCY SAUNDERSON, a subject of the King of Great Britain, residing at Elstow Works, Bedford, in the 5 county of Bedford, England, have invented new and useful Improvements in Pumps, of which the following is a specification.

The object of my invention is to construct a simple pump that may be attached to the 10 bottom of a tube and lowered down a well until it rests firm on the bottom with or without any further fixing and proceed to pump by working the tubular pump-rod up and down, the water coming up it. The pump is 15 particularly suitable for Artesian wells and may also be used for all ordinary purposes and as any other lift and force pump. I attain these objects by the mechanism illustrated in the accompanying drawings, in 20 which—

Figure 1 is a vertical elevation of the pump, part of which is in section. Fig. 2 is a view of the air-chamber that may be inserted between the check-valve *i* and the T *l* 25 when the pump is used for an Artesian well. Fig. 3 is a view of another form of base-plate.

In carrying my invention into practice I construct, as shown by the annexed drawings, a base-plate *a* or *a'*, of any suitable size, 30 having a universal joint *b* or *b'* in the center, (or it may be a ball or other free joint,) to which the pump is attached, as from *c*. The tube *e* passes into the pump-barrel *d* and 35 having a suitable piston formed at its lower end to work in the barrel *d*, but leaving the hole up the tube *e* free. A convenient form of piston is formed by screwing the pipe *e* to receive two nuts *g* and fitting with ordinary 40 pump-leathers *f* between them, as shown in Fig. 1. A guide *h* is provided to keep the tube *e* in a parallel line with the pump-barrel *d*. Any ordinary check-valve *i* may be used and screwed to the piece of tube *e*, with 45 the valve opening upward. Into the top of the check-valve *i* I screw the rising main *j*, which is the pump-rod.

The pump is intended to rest on a solid bottom, and at least the strainer part *c* must 50 be submerged in the liquid to be pumped.

It will then be seen that when the rod *j* is drawn upward the check-valve *i* closes and the piston *f* draws the pump-barrel *d* full of water through the strainer *c* and bottom valve *k*, which closes on the rod descending, 55 and this same water is forced through the check-valve *i* and up the tubular rod *j*. It will thus be seen the friction of the rising column of water occurs on the downstroke, with its attendant advantages. To take the 60 water out of the tube *j*, I proceed as follows: At a convenient height I place a T *l* in the pipe, with a horizontal length of wrought-iron or other pipe *n*, of such a length so as to be capable of springing without fracture. Let 65 this pipe be fixed rigid at the outer end *m*, the inner end *n* going up and down with the main *j*. From the fixed end *m* the water may be taken anywhere. Further, a T *o* may be placed in the main *j* for drawing off by means 70 of a valve *p* and as would be the case when used as an ordinary pump. Suitable guides may be placed to guide the pump-rod *j*, if desired, and the rod may be actuated by any method giving a reciprocating action. 75

If it should be desired to fix the pump in a well in the usual manner, it may be done by attaching a base-plate to the bottom of the pump-barrel *d*, as shown by dotted lines *Q*, in which case in place of the strainer *c* I 80 use an ordinary suction-pipe and strainer to reach the water, making the pump to fix as an ordinary lift and force pump—*i. e.*, not self-fixing.

The above-described pump is particularly 85 suitable for Artesian wells, for, having no solid pump-rod, it allows the use of an air vessel, which may be constructed, as in Fig. 2, with a chamber *r* and a tube *u*, screwed into reducing-sockets *s* and *t*, attached to the main 90 *j*, as in Fig. 2, and placed, preferably, just above the check-valve *i*.

What I claim as my invention, and desire to secure by Letters Patent, is—

In combination with a pump and a bottom 95 center pin or spike and a swivel or jointed base-plate, and a perforated tube bolted to a pump-barrel and a tubular piston operating in a guide at the top of the pump-barrel, and the flange-valve to convey the water upward, 100

and the vertical tube and top valve, and the connecting-rod and the top T, for producing the up-and-down motion by a wind-motor, and the horizontal tube fixed at its end to a wall, substantially as described and for the purpose specified.

In testimony whereof I have signed my

name to this specification in the presence of two subscribing witnesses.

HERBERT PERCY SAUNDERSON.
